DESIGN FOR A DUPLEX FACSIMILE MACHINE

Walter Dorwin Teague, Annandale, N. J., assignor
to Finch Telecommunications, Inc., New York,
N. Y., a corporation of Delaware

Application June 6, 1940, Serial No. 92,846

Term of patent 14 years

To all whom it may concern:

Be it known that I, Walter Dorwin Teague, a citizen of the United States, residing at Annandale, in the county of Hunterdon and State of New Jersey, have invented a new, original, and ornamental Design for a Duplex Facsimile Machine, of which the following is a specification, reference being had to the accompanying drawing, forming a part thereof.

Figure 1 is a front view in perspective of a duplex facsimile machine showing my new design.

Figure 2 is a side view of the duplex facsimile machine.

The two sides of the machine are substantially similar in appearance, and the back and bottom of the machine are substantially plain.

I claim:

The ornamental design for a facsimile machine, as shown and described.

WALTER DORWIN TEAGUE.
